US00D869534S

(12) **United States Design Patent** (10) **Patent No.:** **US D869,534 S**
Day (45) **Date of Patent:** **** Dec. 10, 2019**

(54) **CONTACT LENS**

(71) Applicant: **Novartis AG**, Basel (CH)

(72) Inventor: **Ellen A. Day**, Alpharetta, GA (US)

(73) Assignee: **Novartis AG**, Basel (CH)

(**) Term: **15 Years**

(21) Appl. No.: **29/600,517**

(22) Filed: **Apr. 13, 2017**

(51) **LOC (12) Cl. 16-06**

(52) **U.S. Cl.**

USPC **D16/101**

(58) **Field of Classification Search**

(57) **CLAIM**

The ornamental design of a contact lens, as shown and described.

DESCRIPTION

FIG. 1 is a front planar view of a contact lens showing my new design;

FIG. 2 is a right side view of the contact lens; and,

FIG. 3 is a left side view of the contact lens.

The broken lines shown in the figure Drawings that are immediately adjacent to the unshaded areas represent the bounds of the claim; the broken lines form no part of the claimed design.

1 Claim, 3 Drawing Sheets
